UNITED STATES PATENT OFFICE

FRANK SUTTIN, OF LOS ANGELES, CALIFORNIA

BRACELET BUCKLE

Application filed October 20, 1928. Serial No. 313,673.

This invention relates to a buckle for a bracelet or wrist band. The general object of the invention is to produce an adjustable buckle which will enable the length of the band of a wrist band or bracelet to be adapted to the circumference of one's wrist. In this connection, it should be understood that the invention is particularly applicable for use in the construction of bracelets for wrist 10 watches. A certain type of bracelet has become popular in which it is unnecessary to disconnect the bracelet in order to remove it from the wrist. This is accomplished by having the buckle formed of three superposed plates which are hinged together. When these plates are separated, they increase the circumference of the bracelet to such an extent as to enable the bracelet to be readily slipped off of the wrist. The body 20 of such a bracelet is commonly formed of a ribbon or a band of metallic mesh.

One of the objects of my invention is to improve the general construction of such a buckle.

One of the objects of this invention is to provide simple means for adjustably connecting the end of this flexible band in the buckle so as to alter the size of the bracelet.

One of the objects of the invention is to 30 provide a construction whereby the plates of the buckle will conceal the adjustment and also prevent accidental falling out of the adjusting pin or screw.

Further objects of the invention will appear hereinafter.

The invention consists in the novel parts and combination of parts to be described hereinafter, all of which contribute to produce an efficient bracelet buckle.

40 A preferred embodiment of the invention is described in the following specification, while the broad scope of the invention is pointed out in the appended claims.

In the drawings:

45 Figure 1 is a perspective showing a buckle

of a bracelet of the type referred to and indicating the band of the bracelet and the wrist watch case in dotted lines. This view shows a buckle in an open condition.

Figure 2 is a longitudinal section through 50 the buckle in its closed position.

Referring to the drawings, the bracelet buckle comprises a sleeve 1 which has the form of an elongated thin box so that it presents a transversely elongated opening 2 at one end into which the end 3 of the wrist band 4 can be thrust. The sleeve 1 is preferably constructed out of a face plate 5, the outer face 6 of which is exposed to view. This plate is of elongated rectangular form and is formed at its side edges with flanges 7. Between these flanges one of the plates 8 that forms the complete buckle is attached on a pivot or hinge connection 9. The sleeve also includes an inner plate 10 that forms the inner side of the sleeve and lies adjacent to the buckle plate 8.

In applying my invention, I provide an adjustable connection on the inner side of the sleeve. For this purpose the inner plate 10 has a plurality of openings 11 which are disposed in a row extending longitudinally with the sleeve 1. Cooperating with these openings I provide a removable pin 12 which may be inserted in any one of the openings. The end 3 of the band is preferably provided with a small bushing or eyelet 13 which forms a guide through the mesh of the band to receive the pin 12. When the buckle is to be adjusted, it is opened up as indicated in Figure 1, and the pin 12 is removed and the end 3 of the band 4 is then moved in or out as may be necessary to adapt the length of the bracelet to one's wrist. In making this adjustment, the eyelet 13 is aligned with any one of the openings 11 and the pin 12 is then slipped into place.

If desired, a screw may be used instead of a pin 12, but this would increase the cost of the construction. The buckle plate 8, when

the buckle is closed, lies against the head of the pin 12 and prevents it from coming out.

The plate 8 of the buckle may be considered an intermediate plate as it lies between the sleeve 1 and the innermost plate 14 of the complete buckle. The plates 8 and 14 are connected at one end by a hinge connection 15 and the other end of the plate 14 has a hinge connection 16 with the other end of the

10 wrist band 4.

Any suitable releasable means may be employed for holding the buckle in its closed position, as indicated in Figure 2. In the present buckle I provide a transverse bolster 17 between the flanges 7 at one end of the sleeve 1 and this bolster snaps into a transverse socket 18 which is of substantially tubular form (see Figure 2), with one side cut away to form a gap, or throat, 19 through 15 which the bolster 17 passes when the buckle is snapped into its closed position. (See Figure 2.)

I claim:

1. In a buckle for a bracelet or the like, the combination of a sleeve having a transversely elongated opening in the end thereof, a band of flexible material having one end thereof extending into the end of the sleeve, said sleeve having an inner wall forming a 25 fixed part of the sleeve with a plurality of openings through said inner wall, a removable pin received in any one of said openings and extending into the end of the band to secure the same in the sleeve, and a plate 30 connected with the sleeve, folding against the inner face of the sleeve and concealing the outer end of the pin, to retain the same, said plate having means for attaching the same to the other end of said band.
2. In a buckle for a bracelet or the like, the combination of a sleeve having a transversely elongated opening in the end thereof with a fixed inner wall, a band formed of mesh having one end thereof extending into 45 the end of the sleeve, said inner wall having a plurality of openings passing through the same and disposed in a row extending longitudinally with the sleeve, a removable pin extending at right angles to the plane of the 50 said wall received in any one of said openings and extending through the end of the band to secure the same in the sleeve, said buckle having means for attaching it to the other end of said band.
3. In a buckle for a bracelet or the like, the combination of a sleeve having a transversely elongated opening in the end thereof, a flexible wrist band with one of its ends extending into the end of the sleeve, said sleeve 60 having an inner wall with its flat side against the side of the band and having a row of openings extending longitudinally of the sleeve, a removable pin received in any one of said 65 openings and extending into the end of the band at right angles to the plane of the band

to secure the same in the sleeve, an intermediate plate having a hinge connection at one end with the sleeve toward one end thereof and folding against the inner face of the sleeve to retain the said pin, and an inner hinge plate hinged to the outer end of the intermediate plate, and releasable fastening means for latching one end of the sleeve to the adjacent end of the said inner plate, said inner hinged plate having means for attaching the same to the other end of the band.

4. In a buckle for a bracelet or the like, the combination of a sleeve having four fixed walls, and having a transversely elongated opening in the end thereof, a band of flexible material with one end thereof extending into the end of the sleeve, said sleeve having an adjustable connection on its inner face passing through the said flexible end, for adjustably securing the said end of the band in the sleeve, and a plate secured to the sleeve and folding over the adjustable connection, and having means for attaching the same to the other end of the band.

5. In a buckle for a bracelet or the like, the combination of a sleeve having a transversely elongated opening in the end thereof, a band of flexible material with one of its ends extending into the end of the sleeve, means for securing the end of the band to the sleeve, said sleeve having a pair of oppositely disposed flanges and a transverse bolster connecting the same at the end remote from the opening end of the sleeve, an intermediate hinged plate pivoted between said flanges to fold against the inner side of the sleeve, and an inner hinged plate having a hinge connection with the intermediate plate and having means to snap over the said bolster to hold the plates against the sleeve, said inner hinged plate having means for attaching the same to the other end of the band.

6. In a buckle for a bracelet or the like, the combination of a plate having flanges at its upper and lower edges, a band having one end thereof secured at one end of the plate, an intermediate hinged plate pivoted between the flanges toward the other end of the first named plate, a bolster connecting the said flanges near the pivoted end of the intermediate plate, an inner hinged plate having a hinge connection with the intermediate plate so that said intermediate plate and said inner hinge plate can fold against the inner face of the first named plate, said inner hinged plate having means to snap over the said bolster to hold the plates together, and also having means for attaching the same to the other end of the band.

7. In a buckle for a bracelet or the like, the combination of a sleeve having an inside wall and an outside wall with a transversely elongated opening in the end thereof between said walls, a band of flexible material with one of its flexible ends extending into one end

of the sleeve, means for securing the said flexible end of the band to the sleeve, said sleeve having a pair of oppositely disposed flanges, an intermediate hinge plate pivoted between said flanges to fold against the inside wall of the sleeve and an inner hinge plate having a hinge connection with the intermediate plate, and means for securing the other end of the band to the other end of said inner hinge plate, said inner hinge plate and said flanges having cooperating snap means to hold the plates against the sleeve.

Signed at Los Angeles, Calif., this 11th day of Oct., 1928.
